ELECTRICAL SWITCH APPARATUS FOR OPERATING DEVICES ON AIRCRAFT, AND OTHER PURPOSES

Henry Trevaskis, Solihull, England, assignor to
Dunlop Rubber Company Limited, London,
England, a British company

Application October 9, 1943, Serial No. 505,702
In Great Britain August 29, 1942

8 Claims. (Cl. 200—157)

My invention relates to electrical switch apparatus for effecting collective or selective actuation of a plurality of electrical circuits or devices, and particularly relates to apparatus for controlling the operation of automatic guns on aircraft in conjunction with a cine camera. The invention has for its object to enable such camera to be operated independently of such guns and to ensure that the camera is operated automatically with the guns when any or all of the guns are caused to fire. The invention also embodies a safety device whereby the guns are prevented from being fired while the operation of the camera is permitted.

In my present invention, I provide switches for controlling or operating electric circuits for guns or other apparatus and a pressure plate to close said switches either singly or selectively by localized pressure on said plate or collectively by pressure distributed between or among said switches. A separate switch, for a camera controlling circuit, may also be operated by said pressure plate when pressure is applied to operate said gun operating switches either severally or collectively, or may be operated by selected local pressure independently of said gun operated switches. My invention also comprises a safety plate movable to a position to expose the pressure areas controlling the gun operating switches or to a position to cover these areas and expose only the selective camera operating switch area of the pressure plate and at the same time to open a safety switch which renders the circuits of the gun switches inoperative. It will be understood that these switches may be of any suitable type and that the safety switch may be operated by the safety plate through any suitable mechanism.

In order that the said invention may be easily understood and readily carried into effect, the same will now be described with reference to the accompanying drawings in which:

Fig. 1 is a sectional view of the apparatus on the line A—A of Fig. 2;

Fig. 2 is a plan view of the apparatus shown in Fig. 1;

Fig. 3 is a plan view of the apparatus with the pressure plate and flap removed; and

Fig. 4 is a part sectional view on the line B—B of Fig. 3.

Referring to the drawings a convenient embodiment of the invention comprises a housing having an elongated trough 1 of insulating material housing the various switches, and a cylindrical body portion 2, merging at one end into

the base of the trough as shown in Figs. 1 and 4. The body portion 2 is shaped to pass a multiple cable through its free end which is threaded to engage a cap 3, Fig. 1, by which the body portion is clamped to a flying control handle 4, Fig. 1. The trough is closed by a pressure plate 5, Figs. 1, 2 and 4 which conceals the switch mechanism and which is mounted in the trough so that the pressure plate can be bodily or angularly displaced by thumb pressure applied to it at one of four areas 5a, 5b, 5c, 5d, Fig. 2, such angular displacement serving to operate one or more electrical switches housed in the trough.

In addition to the pressure plate 5 manually operable means are provided in the form of a flap 6, Figs. 1 and 2, which is hinged to the housing to extend substantially across the centre of the pressure plate so as to fold down upon a portion of the plate and thus to act as a safety device which prevents thumb pressure being applied thereto at 5a, 5b, or 5c which control the gun switches that is to three of the four areas in the "safe" position of the flap, while permitting the application of such pressure to the fourth remaining area 5d which may operate the camera switch. The flap 6 is shown in a mid-open position in Fig. 2, but in the firing position of the flap shown by dotted lines in Fig. 2 the three pressure plate areas 5a, 5b, 5c are exposed to permit thumb or finger pressure to be applied to two of these areas independently as at 5a or 5b whereby selective actuation may be effected of two gun operating switches 7 and 8, Fig. 3, or to a third area 5c whereby collective actuation of the same two switches is effected. The switches 7 and 8 each controls the firing of a particular gun or group of guns, whereas pressure applied to the third area 5c serves to operate both these switches and the guns connected thereto simultaneously.

The fourth area 5d of the pressure plate which is exposed when the hinged flap 6 is in the safe position controls the operation of a third operating switch mechanism 13—13e of a cine camera control circuit. This mechanism includes a bowed spring 13d and a plate 13, preferably of insulating material, supported thereon and depressed by pressure on the area 5d. Although the flap when moved to the firing position covers the fourth area 5d of the pressure plate 5 and only exposes the areas 5a, 5b, 5c, pressure applied to any of these three exposed areas also displaces the plate 13 to deflect and close the camera switch so that the camera is always auto-

matically operated in conjunction with any or all of the guns.

Movement of the hinged flap 6 from the safe position covering the multi-area side of the pressure plate to the firing position shown in dotted lines in Fig. 2 also effects actuation of a master switch for connecting or disconnecting the supply of electric current to both the gun operating switches 7 and 8 independently of movement of the pressure plate. When the flap is in the safe position the master switch is opened and when the flap is in the firing position the master switch is closed.

The master switch, Fig. 3, comprises a hook shaped spring loaded member 9 having a contact 9a at the end of its shank and is pivotally held at the bight of the hook by a peg 11 which has a rotatable stem 11a in the bight of the member 9. The peg 11 and the stem 11a are mounted in a corner of the trough 1 so that the member 9 may swing the contact 9a toward or from a stationary contact 9b to make and break a circuit to both of the gun operating circuits. The stem or spindle 11a has a sidewise tongue 11b radial to the axis of rotation of the spindle 11a and notched at its free end to receive the free end of a spring 11c, the other end of which is secured to the member 9 near the contact 9a. The spindle 11a is also provided with a knife edge 11d which bears against the bight of the member 9. The result is that when the spindle 11a is rotated in one direction it causes the contact 9a to snap away from the contact 9b to break the circuit and when turned in the opposite direction causes the contact 9a to snap into contact with the terminal 9b the spring passing through the dead center between these two movements.

The spindle 11a is rotated by the hinged flap 6 being rotated to the position shown in Fig. 3 to cause a quick break of the circuit when the flap is moved to safety position to cover the areas 5a, b, and c, and being moved in the opposite direction when the flap is moved to the broken line position, Fig. 2. For this purpose the flap 6 is rotatably supported by trunnions 6a and 6b, the trunnion 6a being mounted in a pin 6c and the trunnion 6b in the pin 11 and having a suitable transmission to the spindle 11b. Any suitable connection may be used and the details are omitted from the drawings for the sake of clearness.

The gun operating switches 7 and 8 coact with the switch plate 13 which is positioned parallel to the bottom of the trough and carried on a perpendicular hollow plunger 16 sliding in a flanged sleeve 15. The switch plate 13 is displaceable bodily downwardly towards the base of the trough against the load of the bowed spring 13d carried by the under surface of the switch plate 13 to cause the spring to be flexed upwardly so that a camera circuit contact 13e, Fig. 1, at the centre of the bowed spring makes a quick upward movement into electrical contact with the overhanging portion of the fixed contact 9b referred to above.

The switch plate 13 has two projecting limbs 13a, 13b which lie beneath and are spaced from two ball contacts 14 formed on the upstanding ends of the gun switches 7 and 8 which yieldingly support the pressure plate 5 under the load of springs 10, Fig. 4; each of these switches 7 and 8 forms part of an electrical circuit to a single gun or group of guns. The switch plate 13 also has a projection 13c at the side opposite to said limbs and co-acting with a stud or projection not shown on the under side of the fourth area 5d of the

pressure plate 5 so that pressure applied to this area 5d actuates the camera switch 13d.

The main switch plate 13 and the electrical leads 17 to the various switch contacts are carried by the flanged sleeve 15 and by a cylindrical plug 15a secured to and within the free end of the cylindrical body portion 2 of the housing.

It will be understood that the switches 14 connect two separate circuits through the lead wire 10 17 and the contact 9a with the return contact 9b. This contact 9b may be connected in the circuit through any suitable connection as, for example, through the binding post 9c, Fig. 4. The plate 13 is not concerned in the operation of either of the switches 14 but is merely so positioned that it will be depressed when either of these switches 14 is depressed and it will, therefore, cause a bowing of the spring 13d. The spring 13d connects the contact 13 with a circuit through the camera so that when this contact is bowed upwardly to meet the contact plate 9b a circuit will pass through the camera and thence return through the plate or contact 9b and the binding post 9c. It will be apparent, therefore, that the plate 9b acts as a common return contact for each of the gun circuits connected with it through the contact 9a and also for the camera circuit when the latter is connected to the plate 9b through the contact 13 and the bowed spring 15d. There will, therefore, be one return circuit in contact with the contact plate 9b and three separate branch circuits, one for each of the two guns and one for the camera.

The operation of the apparatus for controlling automatic guns and a camera on aircraft is as follows: When it is desired to operate the camera without the guns the flap 6 is thrown over to the safety position to cover the pressure areas 5a, 5b, 5c shown on the right hand side of the pressure plate 5. The master switch 9 is opened by this movement of the flap to render the gun operating switches 7 and 8 "dead" and the left hand portion 5d of the pressure plate 5 is exposed for the application of finger or thumb pressure, whereby the pressure plate may be moved to complete only the camera circuit normally interrupted by the bowed spring 13d carried on the switch plate member 13.

On throwing the flap over to the firing position 50 on the left hand side the master switch 9 is closed, thus rendering the gun operating switches 7 and 8 "alive," and exposing only that multi-area portion of the pressure plate which may be depressed by local pressure so as selectively or 55 collectively to operate one or both of the gun switches. At the same time the camera switch is automatically closed to operate the camera by the deflection of the bowed spring 13d to complete the camera circuit.

Having described my invention what I claim is:

1. Electrical switch apparatus in the form of a unit comprising a housing having a plurality of operating switches, a master switch, a pressure plate movable to operate one or more of said operating switches, and means operative on said master switch to permit the selective or collective operation of said operating switches.

2. Apparatus according to claim 1 wherein said means comprise a flap which is hinged substantially across the centre of the pressure plate and is movable between two positions in each of which a portion of the surface of said plate is covered by the flap.

3. Electrical switch apparatus comprising a pressure plate, a pair of spring loaded switch

75

members contacting the undersurface of said pressure plate and displaceable singly or together by surface pressure on the plate, a single switch member plate normally spaced from the free ends of said switch member and a supporting plunger positioned in sliding contact within a portion of the housing, said switch members making electrical contact with said plate when depressed.

4. Electrical switch apparatus comprising a housing, three operating switches spaced in said housing, a pressure plate movable to operate said switches, two of said switches having operating elements positioned below spaced areas of said pressure plate to permit said switches to be operated independently by selective depression of said areas and the remaining switch being positioned to be operated by a depression of said plate intermediate said spaced areas and means comprising a hinged flap to cover or uncover said spaced areas of said pressure plate.

5. Electrical switch apparatus which comprises a housing having a pair of switches, said switches being spaced apart, a pressure plate having spaced pressure areas above said switches to operate said switches severally by selected depression of said areas, a master switch controlling both said switches, an independent switch in said housing, said independent switch being positioned between said spaced areas to be operated by depression of either of said areas and means comprising a hinged flap to cover the spaced areas

of said pressure plate and to open said master switch when in one position and to uncover said spaced areas and close said master switch when in an alternative position.

6. Electrical switch apparatus comprising a housing, a pressure plate in said housing, a pair of spring loaded switch members contacting the undersurface of said pressure plate at separated areas and displaceable singly by pressure on a selected one of said areas or together by surface pressure between said areas, a single switch member plate beneath and normally spaced from the free ends of said switch members, a supporting plunger for said switch member plate in sliding contact within a portion of the housing, said switch members making electrical contact with said switch member plate when depressed, a spring member supporting said switch member plate and a third switch actuated by said switch member upon depression of said switch member plate.

7. The switch of claim 6 in which said spring member is a bowed spring and said third switch is carried by said spring to come into contact with said switch member plate when the latter is depressed.

8. The switch of claim 6 in which said pressure plate contacts said switch member plate at an area out of alignment with said spring loaded switch members.

HENRY TREVASKIS.
